CALENDAR.

No. 482,929.

Patented Sept. 20, 1892.

Fig. 1.

Calendar from the Commencement of the Christian Era forward and backward
Indefinitely
Old Style and New Style
When not in use for verifying dates keep this Calendar adjusted
for the
Leap Year Current Year **a** Common Years

Fig. 1. a

New Style Dates
Directions for using tables
No 1 and No 2
If the given date be less
than 1000000 the centuries
will be expressed by 0, 1, 2 or 3
if it is 1000000 or more
divide the centuries by 4 and
the remainder (of century
expressed) will be expressed
by 1, 2, 3 or 4
On the column of days
divide the number by 7 and
the remainder will remain under
the second or third
line with the day of
the week on which the
year came or will come in
August the 13th comes
to October the 4th at the top
you have the calendar
for the given year
We call the figures to the
left of the table the centuries
and the units and tens
figures the years

۱۰۰

Fig. 19.

Obs. 1. Call the years which are dotted are leap years and correspond to the months on the left over which is written "Common Years".
Obs. 2. Call the years which are dotted are common years and correspond to the months on the left over which is written "Common Years".
Obs. 3. For all century years whose century remainder is 1, 2, or 3, take (00) for the given year because they are Common years.
Obs. 4. For all century years whose century remainder is 0, take 00 for the given year, because they are leap years + 00 for three days before Christ, because they are Common years.

UNITED STATES PATENT OFFICE.

CHARLES H. RENDELL AND EDWIN S. PINNEY, OF TULARE CITY, CALIFORNIA.

CALENDAR.

SPECIFICATION forming part of Letters Patent No. 482,929, dated September 20, 1892.

Application filed July 12, 1892. Serial No. 439,826. (No model.)

To all whom it may concern:

Be it known that we, CHARLES H. RENDELL and EDWIN S. PINNEY, citizens of the United States, residing at Tulare City, in the county 5 of Tulare and State of California, have invented new and useful Improvements in Calendars, of which the following is a specification.

This invention relates generally to calendars, and particularly to that class thereof 10 known as "perpetual calendars."

The object of our invention is to provide a simple and efficient calendar of this description which, in conjunction with an exceedingly-simple table, can be operated to produce a 15 complete calendar for any year either before or after Christ, and according to either the old or the new style of computation.

Our invention consists in the peculiar construction and arrangement of the various 20 parts, all of which will be fully described hereinafter, and pointed out in the claims.

In the drawings forming a part of this specification, Figure 1 is a face view of our improved calendar set for the year 1892. Fig. 25 2 is a vertical section of the same, and Fig. 3 is a detail view of the sliding card detached.

In carrying out our invention we employ a sheet of card-board A of suitable size and thickness, and in the center of the same produce one or a series of vertical slots a. In 30 the drawings we have shown three such slots, that being the number usually employed. Upon each side of the slots a are designated the days of the year arranged horizontally, according to the month, and vertically, according 35 to the days of the week, as most clearly shown. The designations are upon each side of the slots, and it will be observed that while the months run from left to right upon the right of the slots they run from right to left upon the left of the slots. The days upon the right are arranged for an ordinary year, while upon the left they are arranged for leap-years. Parallel guide-strips B B are secured to the 40 rear face of the card above and below the slots, and sliding between these strips is a card C, having the days of the week printed upon its front face in vertical order and in seven distinct columns, each succeeding column to the 45 right beginning with the second day of the preceding column. By this means every pos-

sible combination of days in proper order is attained. The days are arranged in as many groups as there are slots, and only one week at a time shows through each slot. The card 55 is adapted to be slid horizontally back and forth, and for this purpose the strips are rabbed, as shown at b, thus permitting the card to slide, but preventing its displacement.

D and D' indicate tables attached to the 60 card to illustrate the manner of using the same, and E indicates a series of schedule-leaves attached to the card and used in connection therewith, said leaves having tables marked thereon for computing dates before 65 and after Christ, and according to the old and new styles, respectively, each leaf having a separate table.

As before stated, the calendar is set for 1892; but we will suppose, for the sake of illustration, that it is desired to find what day July 4, 1892, will come on. By referring to table D we are instructed to divide all centuries after four hundred by four, and by dividing eighteen by four we have two for a remainder. 70 This indicates that we must look in column two of the centuries upon schedule-leaf E, and then by tracing the horizontal column across until we find "92" we see that 1892 came in on Friday. The card C is then adjusted so as 75 to bring Friday opposite January 1. From schedule E it will be seen that "92" has a dot in front of it, thus ".92," which indicates that it is a leap-year, and for leap-years we are referred to the calendar at the left. Now coming down to the month of July we find that the fourth day will come on Monday.

Further details of the tables are not necessary, as it can be seen that any year can be quickly and easily found and any day thereof 80 determined.

We do not wish to limit ourselves to the precise construction shown, but may vary the same somewhat without departing from the broad principles of our invention.

Having thus described our invention, what we claim is—

1. In a calendar of the class described, the combination of a card having a central slot or slots and the days of the year marked upon opposite sides of said slot or slots and a card adapted to slide upon the back of the

main card, said sliding card having the days of the week marked thereon in different columns, all substantially as shown and described.

5 2. In a calendar of the class described, the combination of a main card having a central slot or slots, the days of the ordinary year arranged upon one side of the slot or slots and the days of the leap-year arranged upon the opposite side of the slot or slots and in re-

verse order, the strips upon the rear face of the main card, and the sliding card having the days of the week arranged thereon in differing columns, all substantially as shown and described.
